UNITED STATES PATENT OFFICE.

JOSEPH E. DRAKE, OF BLUE RAPIDS, KANSAS.

GRAIN-CAR DOOR.

Application filed September 14, 1922. Serial No. 588,193.

To all whom it may concern:

Be it known that I, JOSEPH E. DRAKE, a citizen of the United States of America, and a resident of Blue Rapids, in the county of 5 Marshall and State of Kansas, have invented a new and Improved Grain-Car Door, of which the following is a description.

My invention has for its general object 10 to provide an auxiliary grain car door to be employed beneath any approved main car door, said auxiliary door adapted to be detachably secured at its ends to the sides of the door frame and provided with an opening 15 controlled by a closure so that the auxiliary door while in position will permit the flow of grain or other bulk material and be bodily removable when sufficient of the material has run from the car.

20 The present invention is designed more especially as an improvement on the grain car door forming the subject matter of an application filed by me March 17, 1922, Serial Number 544,501 and has for its prime 25 object to provide on the auxiliary door, rest means for the main built-on grain door, said object and others as will appear being attained in a manner and by means hereinafter fully set forth.

30 Reference is to be had to the accompanying drawings forming a part of this specification, it being understood that the drawings are merely illustrative of one example of the invention.

35 Figure 1 is an exterior view of a grain car door embodying my invention showing the same emplaced;

Figure 2 is a horizontal section on the line 2—2, Figure 1, showing the auxiliary 40 door in closed and fastened position;

Figure 3 is a view similar to Figure 2 but showing the closure of the auxiliary door swung away from the opening in said door and showing the sections of the auxiliary 45 door flexed;

Figure 4 is a longitudinal vertical section taken on the line 4—4, Figure 5;

Figure 5 is a transverse vertical section on the line 5—5, Figure 1.

50 In carrying out my invention in accordance with the illustrated example my improved auxiliary door designated generally by the numeral 10 has a width to be disposed in the usual door opening 11 of a car 12 to overlap the door frame, said auxiliary door

being positioned at the bottom of the opening beneath the main door 13 of any approved construction.

Said auxiliary door includes two sections 14 contacting at their opposed ends and a closure 15 for the space or opening presented at the juncture of said sections, said closure 15 being hinged as at 15^a to one section 14 and adapted to overlap the other section when the two sections are alined. The sections 14 at their opposed ends have respectively upper and lower hinge leaves 16 having face members 16^a rigid therewith and connected by hinge pins 17 so that the door may "break" or flex outwardly at the center.

In accordance with the present invention I provide on the auxiliary door composed of the sections 14 bar sections 20 each having slots 21 extending obliquely, there being a pair of such slots in each bar section 20, the slots 21 in a section being opposite to the slots in the other section. Said slots receive transverse pins 120 passing through adjacent fixed parts of the auxiliary door sections 14. Knobs 121 serve as handles for sliding the bar sections 20. Said bar sections 20 are disposed on the auxiliary door in the vertical plane of the built-on grain door 13 and may be moved longitudinally to cause the engagement with the pins 120 at the slots 21 to raise or lower the bar sections 20 for contacting with the grain door 13 at the lower edge or said sections 20 may be so moved as to disengage the grain door 13. The sections 20 constitute a rest for the door 13.

80 In order to lock the auxiliary door with the sections 14 alined and the closure 15 swung to the closed position between the 85 said sections, I provide a lock bar 22 of a length to extend horizontally across the closure 15 and overlap the sections 14. Said bar is swingably secured at one end as by a U-bolt 23 which passes through one door section 14 and through reinforcing plates 24 applied to said section at the inner and outer surfaces thereof. At the opposite end the lock bar 22 is adapted to be held by a latch 25 hinged as at 26 to the opposite 100 door section. The bar 22 is U-shaped or channeled in cross section and accommodates in the channel the latch 25. A sliding keeper 27 on the lock bar 22 is adapted to be slipped over the latch 25 when the latter 105

110

is in the latching position against the bar 22.

With an auxiliary door constructed as described the same is placed in position in the doorway at the bottom. When the grain or other bulk material is to be discharged the lock bar 22 is released and the closure 15 is swung on its hinge to the open position to permit the material to flow outwardly between the door sections 14. The auxiliary door 10 is removable bodily, the removal being effected by flexing the door at its hinge 17. Rest sections 20 are lowered from engagement with door 13 in removing auxiliary door 10.

15 The auxiliary door 10 is rounded or bevelled at the lower edge as at 10^a and at the upper edge as at 10^b, the lower bevel engaging the sill plate 12^a provided on the car 12 of the door opening 11 as usual, and the upper bevel being presented to the lower edge of the main door 13. At the top the closure 15 extends above the auxiliary door 10 and its hinge member 16 to a height to overlap the main door 13.

20 25 A block 28 is secured to the floor of the car 12 just inward from the plane of the auxiliary door 10 at the medial line of said auxiliary door to constitute a stop in the placing of the door in position beneath the main door 13.

25 The car is prepared for loading as follows: The auxiliary door 10 is placed in position as described and the bar sections 20 are moved to the raised position. Then the first ordinary grain door section is placed in position resting upon the sections 20 and said ordinary grain door section is then nailed solidly to the doorway post.

40 It will be observed that the slots 21 are at only a slight angle and materially within the angle of repose for which reason there is no tendency whatever of the plates to be moved to a lowered position under the weight of the main door 13.

45 I would state in conclusion that while the illustrated example constitutes a practical embodiment of my invention, I do not limit myself strictly to the exact details herein illustrated; since, manifestly, the same can be considerably varied without departure from the spirit of the invention as defined in the appended claims.

Having thus described my invention, I claim:

1. An auxiliary grain car door adapted to be detachably secured at its ends in a door opening beneath a main door, said auxiliary door including sections hinged together and presenting an opening therebetween, a closure for said opening hinged to one of said sections and movable to close or open position, and means on said sections of the auxiliary door movable in a vertical plane to engage the main door above and constitute a support therefor until said main door is nailed in position.

2. An auxiliary grain door adapted to be detachably secured in the door opening of a grain car beneath the main door, said auxiliary door having means to afford temporary support for the main door, said means being movable on the auxiliary door and into engagement with the main door to constitute a temporary support therefor until said main door is nailed in position.

75 3. An auxiliary grain door adapted to be detachably secured in the door opening of a grain car beneath the main door, and a support for the main door mounted on the auxiliary door, said rest having oblique slots 80 and the auxiliary door having pins passing through said slots so that the movement of said support will serve to move the same into contact with the bottom of the main door to hold said main door temporarily in position 85 until nailed.

4. An auxiliary grain car door adapted to be detachably secured in the door opening of the grain car beneath the main door, said auxiliary door including sections hinged together, and an element on each section of the auxiliary door at the top and movable in a vertical plane to contact with the main door and constitute a support therefor or to be lowered out of contact with the main door, said element each having a pair of oblique slots therein and the auxiliary door sections having pins passing through said slots so that a longitudinal movement of said elements will impart vertical movement to engage said main door for temporarily holding said main door until nailed.

JOSEPH E. DRAKE.
